PROCESS FOR DRY CLEANING

Dennis P. Allison, Vicksburg, Miss.

Application January 3, 1940, Serial No. 312,283

1 Claim. (Cl. 8—142)

This invention relates to a solution, process and apparatus for dry cleaning.

At present the usual procedure of dry cleaning by completely dry process consists of entering fabrics in a washer by weight according to the size of the washer and the amount of solvent therein. These fabrics are given a preliminary run of from five to fifteen minutes with a circulating pump operating. This removes loose or easily soluble soil of solvent solubility. The circulating pump is then stopped and a detergent, or cleaning aid, for the solvent is then applied to the fabrics for the purpose of aiding in removing imbedded or stubborn soil. This procedure is continued for from ten to thirty minutes according to the amount of soil to be suspended from the fabrics. The circulating pump is then started again for clearing this suspended soil and detergent from the washer and depositing the same on the screens of a filter in closed circuit circulation with the washer. This step usually requires from ten to thirty minutes determined by color or clarity of the filtered solvent in a sight glass in the circulation circuit. The above procedure removes to a great degree soil of solvent solubility from the fabric, but leaves the water soluble stains such as, perspiration, fruit juices, and the other stains of like nature.

With the above in mind my invention provides a process adapted to remove water soluble stains while using the same procedure above explained without changing washers, or solvents, and without the addition of water proofing agents or solvent soluble moisture carriers to the solvent.

My process includes the usual procedure above outlined, which employs a detergent for the purpose of a cleaning aid to the solvent, and then clears the detergent and soil from the circulation by the use of a filter. Then, and this is the new step, I humidify the solvent in the washer with a detergent solution of fatty alcohol sulphate in water form, for the purpose of removing stains of water soluble nature. This solution has all the practical advantages of soap and water without the disadvantages of soap as it does not hydrolyze to form an alkaline solution which is damaging to both fabrics and colors.

Sulphated fatty alcohol is manufactured and sold by different chemical manufacturers under several trade names such as Arysol, Fymolol Salt (Orvus W. A. Paste), or Musolite, and other trade names. The product has been used for various purposes, especially for its penetrating qualities due to the fact that a very small percentage near-

ly completely destroys the surface tension of water and for its more remarkable quality of being a very effective detergent, not being greatly changed for this purpose by even concentrated acids.

5 Sulphated fatty alcohol plays an important part in my process as it serves at least three different purposes. First, it reduces the surface tension of water to which it is applied, causing it to be a practical carrier for itself in combination with dry cleaning fluids of volatile hydrocarbons. Second, when small quantities of water, treated with this product, are administered to dry cleaning solvent according to my process, the 10 solution due to retarded surface tension, breaks into small bubbles under agitation of the solvent in circulation, and causes it to stay suspended in this form for a long enough period of time for its entrance into the washer and uniform absorption by the fabrics. Third, sulphated fatty 15 alcohol possesses remarkable penetrating qualities, and since it is suspended in the solvent in a very fine state, it is absorbed faster and more uniformly than plain water, giving the desired results, where needed, without using water repellents to assure even penetration.

The penetrating quality of my sulphated fatty alcohol solution assures practically all of the solution being absorbed by the fabric, consequently 20 reducing the colloidal moisture content of the solvent in use, to a very fine point. This is of great importance due to the fact that my process calls for cleaning by the completely dry process first, and then performing a semi-dry process, so 25 that I am able to run succeeding loads of fabrics without changing machines or solvents. This penetrating quality is also of advantage since it keeps moisture of any amount from leaving the washer and being deposited on the 30 screens of the filter by the pump circulation.

35 My sulphated fatty alcohol solution, besides reducing surface tension and possessing great penetrating qualities, has another advantage, that of possessing and carrying useful detergent 40 action to fabrics in moisture form. This action is accomplished in dry cleaning due to the fact that this solution is not affected by acid or alkali that may be present in the area of absorption, or 45 free in the solvent. Also this solution does not affect fabrics or colors that are not affected by plain water. In other words I am able to get soap and water results on water soluble stains in 50 dry cleaning without the hazards of water, am able to hasten the dry cleaning operation, and 55 am able to use minimum moisture.

The humidifying detergent solution according to my invention is a small percentage, about two percent, of sulphated fatty alcohol detergent, and about 98 percent water. The percentage of water may vary according to the type of trade sulphated fatty alcohol product used, but the usual amount with standards products, such as Arysol or Hymolol Salt is substantially as follows:

Arysol or Hymolol Salt.....ounces... 2
Water.....gallons... 1

The resulting solution is a detergent that will not break down in acids and that will have greatly reduced surface tension. The amount of solution to be applied by my method to the dry cleaning solvent will vary according to the amount of soil of water soluble nature to be removed from fabrics, but the amount need never exceed six percent of the weight of the fabrics. The preferred percent is four percent by weight. These small amounts administered to the dry cleaning machine have, by test, proved to have soil removing qualities of twice the amount of plain water when exposed for the same period of time.

My invention also relates to an apparatus for applying the sulphated fatty alcohol solution to the dry cleaning solvent.

In the circuit of the solvent being used and filtered during the dry cleaning process, all solvent outside of the washer itself is under pressure of varying degrees and with this in mind my apparatus is adapted to inject the solution in the circuit at a point of least pressure which is immediately before entrance to the washer. This point of installation of the apparatus is under slight pressure when the solvent is circulated and the apparatus is adapted to offset this pressure by vacuum to allow the solution to flow into the circuit by gravity.

In the accompanying drawing forming a part of this specification:

Figure 1 is a side elevation of the apparatus, with parts in section, constructed in accordance with the invention.

Figure 2 is a plan view of the fan-shaped nozzle.

Referring now to the drawing in which like characters of reference designate similar parts in the various views, 1 designates a funnel for receiving the sulphated fatty alcohol solution. The funnel is equipped at the lowest point in the bottom with a pipe 2 which is connected to one of the alined branches of a T 3. A valve 4 is connected to the other alined branch of the T by a pipe 18 for regulating flow of the solution to the solvent circulating line. The valve 4 is equipped at the bottom with a pipe 5 which is screwed into a plug 6 which closes the lateral branch of a T 7. The circulating pipe 8 from the filter (not shown) enters one alined branch of the T 7 while the circulating pipe 13 to the washer (not shown) enters the other alined branch of the T 7.

A pipe 11 is screwed into the plug 6 and connected with the pipe 5. The pipe 11 extends downwardly into the T 7 to about the center thereof where it is equipped with an elbow 9. A pipe 12 is connected to the elbow 9 and terminates in a fan-shaped spray nozzle 14 for release of the solution in the direction of flow of the closed circuit circulation of filtered solvent at a point near the entrance of the solvent to the washer.

A pipe 15 is connected to the lateral branch of the T 3 and is equipped with a valve 16 which

controls entrance of the sulphated fatty alcohol solution to a sight glass 17 which rises from the valve 16 parallel to the funnel 1.

In operation, when the required amount of sulphated fatty alcohol solution is placed in the funnel, the solution is fed into the solvent circulation in the pipe 13, very slowly, by regulation of the valve 4, and is released into the circulation of the solvent by the fan-shaped nozzle at the end of the injector nipple 12, located in the solvent flow line and discharging toward the washer, which latter is the destination of the solvent being circulated. The nozzle serves two purposes, one being to cause a vacuum to form at this point by the solvent rushing past the nozzle, and the other is that by virtue of the nozzle having a narrow opening it releases the solution in a thin fan-shaped sheet which is broken into fine particles by agitation of the solvent in circulation, to enter the washer in suspended form while the circulation is in progress.

It will be understood that the solution must enter the solvent circulation slowly, therefore, the control valve 4 must be set according to the velocity of flow which varies according to the size of filter or pump used. The valve cannot be set to gravity flow before installation, but must be set at the beginning of its first use, and according to the speed of solvent flowing past the outlet of the nozzle. When once set to the size of the pump, it needs no further attention, even when not in use, because the solvent does not back up in the apparatus.

In practice the period of time required to inject a given amount of the sulphated fatty alcohol solution to the solvent and assure suspension may vary slightly. Preferably the control valve 4 may be regulated to release the solution to the solvent circulating line at the rate of one-half pint for every twenty-five gallons of solvent flowing past the nozzle 14. For pump circulation of 1200 gallons an hour, it will require approximately five minutes to inject, in suspended form, one quart of solution. The same percentage of injection may be followed as to faster flow of circulation based on this method of simplified calculation.

It will be pointed out that my sulphated fatty alcohol solution having moisture detergent qualities, can be applied to, and suspended in, solvent of less than one-quarter of one percent free fatty acid content. Above this figure solvent has a definite tendency to carry the solvent residue through the filter and back to the fabrics in the washer. Therefore, solvent kept below one-fourth of one percent of free fatty acid content proves in practice to be better suited for efficient cleaning.

In actual practice, the process is as follows: The fabrics are placed in the washer according to weight as is the usual practice. The circulation of the solvent from the washer to the filter and back to the washer is started and continued for a short period of time to remove loose or surface soil of solvent solubility and the circulation is then stopped. Rotation of the cylinder of the washer is continued while the solvent detergent or cleaning aid is added. The rotation of the washer cylinder in the detergent charged solvent may be continued for from ten to thirty minutes according to the type of fabric being cleaned and amount of soil to be suspended from the same. Absorbent powder is then added to the solvent at the washer or other provided place to be circulated to the filter to remove the detergent or cleaning aid and the soil suspended

by them, on the filter screens. Circulation is then started again and continued until the solvent shows optical clarity in the sight glass provided for this purpose. At this point my step of administering the sulphated fatty alcohol detergent to the solvent at the washer inlet is to be started by placing the required amount of solution in the funnel 1. This solution due to its rapid penetration is instantly absorbed by fabrics as it slowly enters the washer, releasing from the fabrics water soluble stains that have not been removed by the preceding treatment. The treatment of the fabrics in this manner is allowed to continue for approximately two or three minutes after the solution has all entered the solvent. This short period of time has proved sufficient in practice for complete uniform absorption of the solution by the fabrics and the release of stains affected, but can be continued for any length of time without detrimental effect to most fabrics. The load of fabrics is then ready for extraction and de-odorizing to be done preferably at minimum temperature since by having used solvent in its most volatile state it is unnecessary to use high temperatures, and in so doing to remove the possibility of wrinkles from extraction and exposure to sudden high temperatures.

From the above description it is thought that the construction and operation of the invention 30

will be fully understood without further explanation.

What is claimed is:

In a dry cleaning process, subjecting fabrics in a washer to the action of a solvent solution containing a detergent, removing the detergent from the solution by filtration, circulating the filtered solvent solution, introducing sulphated fatty alcohol detergent into the circulating solvent solution in a thin fan-shaped sheet at the washer inlet, controlling the release of the sulphated fatty alcohol detergent to the circulating solvent solution to a ratio of one-half pint to every twenty-five gallons of solvent solution flowing past the point of admission of the sulphated alcohol detergent, such controlled admission and thin fan-shaped sheet form of the admission effecting the breaking up of the sulphated fatty alcohol detergent into fine particles by agitation of the solvent solution in circulation so that the detergent enters the washer in suspended form while the circulation is in progress, maintaining the solvent at less than one quarter of one per cent free fatty acid content while the sulphated fatty alcohol detergent is being applied to and suspended in the solvent solution, and returning the solvent solution with the sulphated fatty alcohol detergent suspended therein to the washer for further treatment of the fabrics.
